mon Weiss, as partners

Application October 26, 1946, Serial No. 705,848

4 Claims. (Cl. 62—89)

1

This invention relates to clothes vaults and particularly to an air-conditioned clothes vault. Conducive to a better understanding of this invention it may be well to point out that it has long been common practice to store valuable wool and fur garments in commercial cold storage vaults during the summer season, where they are protected not only from the ravages of insect larvae but also from the desiccating action of the summer's heat. The value of this type of storage is appreciated by everyone, but heretofore, its high cost and the inconvenience of transporting garments to a central storage vault have restricted its use.

The primary object of this invention, therefore, is to provide a self-contained, portable clothes vault, suitable for home use wherein garments and other articles can be stored at low temperatures unfavorable to the support and propagation of insect life.

Another object is to provide a device of the type described that includes means for maintaining the relative humidity of the enclosed air, within predetermined limits, so that the protected articles will not become dehydrated even after prolonged storage.

These objects of the invention will become apparent from a reading of the following specification and claims together with the accompanying drawings in which the same parts are referred to and indicated by the same reference characters and wherein;

Figure 1 is a perspective view of the clothes vault constituting this invention with a portion broken away to show the arrangement of stored articles within the vault;

Figure 2 is a front elevation of the device with portions broken away to show the structure of the cabinet and the relative positions of the various refrigerating and humidifying units;

Figure 3 is a horizontal cross-sectional view taken along the line and in the direction of the arrows 3—3 of the Figure 2;

Figure 4 is a vertical cross-sectional view taken along the line and in the direction of the arrows 4—4 of the Figure 2, showing one of the garment carriages in an alternate extended position;

Figure 5 is a cross-sectional view, showing the garment carriages and the door in alternate open and closed positions, taken along the line and in the direction of the arrows 5—5 of the Figures 2 and 4;

Figure 6 is an enlarged vertical cross-sectional view of the humidifier unit taken along the line

and in the direction of the arrows 6—6 of the Figure 4; and

Figure 7 is an enlarged cross-sectional view of a portion of the two garment supports showing both their structure and their position in relation to the expansion coil, taken along the line and in the direction of the arrows 7—7 of the Figure 5.

Referring to the drawings there is shown a clothes vault made in accordance with this invention.

Reference character 10 in Figure 1 indicates a cabinet of approximately 20 cubic feet contents. It is fabricated in the manner of a conventional refrigerator, having an outer metal case and an inner metal liner, spaced therefrom, to form a wall cavity approximately 2½ inches wide which is filled with a suitable insulating material of low thermal conductivity. An insulated door 11 having a rubber sealing gasket is fitted to the cabinet in the manner of a conventional refrigerator door. Reference characters 18 and 19 indicate a lock and hinges respectively.

A thermostat 21 and a humidostat 53 are mounted on the inside of the door with their indicating dials mounted on the outside of the door as shown in Figure 2. A cabinet of the type just described has outer overall dimensions of approximately 4.5 feet x 3.5 feet x 2 feet which is a size that permits it to be easily placed in the average house or apartment.

A conventional mechanical refrigerating unit having a compressor, electric motor, condenser, receiving tank and the usual accessory switches and valves is mounted on the bottom 11 of the cabinet 10 within the insulated compartment 31, which is sealed off from the interior of the cabinet. Louvers 37 pass through the side wall 13 and vent this compartment to the outside, serving as passageways for the escape of heat from the condenser, as shown in Figures 2, 3, and 5.

An expansion coil 32 is suspended from the top, 12, of the cabinet by means of the brackets 36 and is connected to the compressor by means of the intake and outlet pipes 34 and 35 respectively. The coil is centrally located between the two side walls 13 and 14, perpendicular to the rear wall 15, thereby dividing the interior of the cabinet into two equal compartments. The expansion coil in its preferred form is fabricated from a continuous length of non-corrosive metal tubing bent back and forth upon itself to form a series of vertically spaced and parallel, horizontal sections of equal length, lying in the same plane and extending downward to form a coil approximately 30 inches long, as indicated in Figures 1.

2, 3 and 4. This style of coil is used because it occupies a minimum of space while at the same time presenting a maximum surface area to the enclosed air.

A thermostat 21 and a humidostat 53 are mounted on the door 17 and electrically connected to the refrigerating unit by means of electrical wiring not shown in the drawings since the method of accomplishing this is well known to those skilled in the art.

A coarse wire grill or screen 33 is mounted approximately one inch from both vertical faces of the expansion coil and parallel thereto. These protective screens not only serve to prevent garments from coming into contact with the expansion coil but also provide a free passageway between the coil and the garments. Air cooled by contact with the coil 32 can fall freely thru this duct to the bottom of the cabinet where it displaces the warmer air. The displaced air circulates up thru the garments, across the top of the cabinet and back to the expansion coil where it is in turn cooled.

Reference character 50 in Figures 1, 2 and 4 indicates a humidifier unit which is in the form of a concave metal trough 51 entirely covered by a porous fabric wick 52 as shown in detail in Figure 6. The humidifier is suspended between the two screens 33 and immediately below the expansion coil 32, so that it will catch all of the water that drips off the expansion coil when it is defrosted. The covering 52 is made of a flat piece of porous wick-like fabric that is closely and continuously fitted to the inner and outer surfaces of the trough. The purpose of this porous covering is to provide a large evaporating surface for the water collected by the trough so that it may be easily and quickly returned to the atmosphere of the closed cabinet.

Two garment supports 40 are suspended from the top 12 of the cabinet as indicated in Figure 2. Each garment support comprises a pair of spaced U-shaped channel tracks 41 with their channels faced toward each other as shown in Figures 5 and 7. These tracks are rigidly suspended from the top 15 by the metal brackets 46 so that their open ends will be positioned just below the top of the door opening, as indicated in Figures 1, 2, 4 and 7. A carriage fabricated from two U-shaped channels 42 joined by a transverse hanger bar 43 is slidably mounted within the paired tracks 41. Garment hangers 44 are used to suspend the garments 45 from the bar 43 as shown in Figure 1.

When the cabinet door is opened to the position indicated by 17a in Figure 5, each carriage can be slid forward along its respective pair of tracks 41 to take the alternate position designated by reference character 42a. This brings the garment bar to the alternate position 43a, beyond the confines of the cabinet, where garments can be conveniently added to or removed from the bar.

A storage compartment 23 is located on the bottom 11 of the cabinet against the right end wall 14 as illustrated in Figures 1, 2, 3 and 5. It is made of sheet metal and has a lid 24 and a vented side wall 25 which enables the cool air from the main compartment to enter and circulate around the articles stored therein. This compartment is used to store articles that cannot be conveniently held on hangers such as blankets, underclothing, scarves, gloves and the like.

The clothes vault just described is operated and used in the following manner: Articles to be

stored in the vault are thoroughly cleaned and brushed and then placed on hangers 44 or packed in the storage compartment 23. The garment bar 43 is pulled out to the position 43a as indicated in Figures 4 and 5 and the hangers 44 are suspended from it. The bar is then slid back into the cabinet where the garments 45 assume the position indicated in Figure 1. It will be seen that the garments are held in a position parallel to the plane of the expansion coil 32 and that the end garments are protected from contact with the expansion coil by the screen 33.

Approximately 4 ounces of water are poured into the humidifier pan 50 when using a vault of the size described. In the case of larger or smaller vaults the quantity of water used is varied accordingly.

The door 17 is closed and locked to prevent tampering by unauthorized persons.

The thermostat 21 is manually set to maintain a temperature of 5° Fahrenheit for 24 hours, which will destroy all moth eggs that were not removed when the garments were cleaned prior to placement in the vault. At the end of 24 hours 25 the thermostat is reset to 40° Fahrenheit and kept at that point throughout the storage period.

Since the cabinet is well insulated and the door gasket forms an air tight seal between the door and the cabinet wall a temperature of 40° Fahrenheit within the cabinet can be easily maintained with only occasional operation of the refrigerating unit. The device will, therefore, be economical to operate.

The thermostat thermometer on the door of 35 the cabinet can be inspected from time to time to check on the temperature being maintained in the cabinet.

The humidostat 53 is set for the desired humidity and its indicator dial is also available for inspection on the face of the cabinet door as shown in Figure 2.

The 4 ounces of water which were placed in the humidifier trough are absorbed by the humidifier wick 52.

45 The humidostat 53 is set to hold the relative humidity in the cabinet between an upper and a lower limit suitable for the articles being stored. The four ounces of water which were placed in the humidifier pan 51 before the vault was closed 50 is calculated to produce too high a relative humidity within the cabinet when evaporated from the wick 52. When this vapor laden warm air comes in contact with the cold surface of the expansion coil it is cooled and its capacity to hold water vapor is reduced. The excess vapor condenses on the expansion coil and is held there in the form of frost. The humidostat is connected as a master controller over the refrigerating unit and can hold the thermostat out of operation until its requirements are satisfied. The manner of doing this is familiar to those skilled in the art and therefore need not be described here.

The refrigerating unit is kept in operation by the humidostat until enough water vapor has been withdrawn from the air and deposited on the expansion coil in the form of frost to reduce the relative humidity of the air to the high limit setting of the humidostat, after which the thermostat is put into control and maintains the set temperature.

Since the coil 32 is always colder than the air immediately in contact with it, it is continuously extracting water vapor from this air. Furthermore since there is a continuous slow circulation of air in the cabinet past the coil the end result

of this combination of circumstances is that the air in the cabinet is slowly dehydrated and its relative humidity falls lower and lower. If this process were permitted to continue uninterrupted the entire 4 ounces of water added to the humidifier would be deposited on the coils and the dry air would then proceed to remove the moisture from the fibers of the garments stored within the cabinet, which would become dry and brittle. However, long before this state is arrived at and as soon as the relative humidity has fallen below the lower limit setting of the humidostat the refrigerating unit is turned off by the humidostat and the expansion coil is caused to defrost. The melted frost drips down into the humidifier unit 50 and is absorbed by the wick 51 which presents a large damp evaporating surface to the dry air. The water again returns to the air as vapor and the defrosting process is permitted to go on until the relative humidity of the air rises to the low limit setting of the humidostat. The humidostat thereupon returns control of the refrigerating unit to the thermostat which again takes over and makes the proper adjustments to maintain the temperature at 40°.

If the relative humidity either rises or falls beyond the limits set by the humidostat, it is automatically brought within the limits by a repetition of the process just described.

This accurate control of the humidity within the cabinet keeps the garment fibres from becoming dehydrated so that furs and woolens are in prime condition when they are removed from the vault at the end of the storage period. In fact they may be in a better condition than they were when originally placed in storage, since garment fibres are often in a dehydrated condition at the end of a winter spent in the dry atmosphere of a steam heated apartment.

It will now be clear that my invention provides a compact, self-contained, portable clothes vault that maintains stored garments in prime condition at a low cost. While my invention has been disclosed in its preferred form; it is to be understood that the specific embodiment thereof as described and illustrated herein is not to be considered in a limited sense as there may be other forms or modifications of the invention which should also be construed to come within the scope of the appended claims.

I claim:

1. A clothes vault comprising in combination, an insulated cabinet having spaced top, bottom, front, rear and side walls, the said front wall having an insulated door hingedly mounted thereon, an air-conditioning means including a humidifying unit and a humidostatically and thermostatically controlled refrigerating unit mounted within the said cabinet, the said refrigerating unit having a vertically extending expansion coil suspended from the top of the cabinet intermediate the said side walls, the said humidifying unit having an evaporating trough disposed below and in close spaced relationship with the expansion coil, capable of collecting the drip from the expansion coil, a protective grill mounted within the cabinet around the said expansion coil

in spaced relation thereto, and garment supports mounted in the cabinet proximate to the expansion coil.

2. A clothes vault comprising in combination, 5 an insulated cabinet having spaced top, bottom, front, rear and side walls, the said front wall having an insulated door hingedly mounted thereon, an air-conditioning means including a humidifying unit and a humidostatically and thermostatically controlled refrigerating unit mounted within the said cabinet, the said refrigerating unit having a vertically extending expansion coil suspended from the top of the cabinet intermediate the said side walls, the said 10 humidifying unit having an evaporating trough disposed below and in close spaced relationship with the expansion coil, capable of collecting the drip from the expansion coil, a protective grill mounted within the cabinet around the said expansion coil in spaced relation thereto, and garment supports mounted in the cabinet proximate to the expansion coil.
- 15 3. A clothes vault of the type defined in claim 2 and further characterized by each garment support having a pair of spaced horizontal tracks suspended from the top wall of the cabinet between the expansion coil and one of the said side walls, and parallel thereto, and a carriage including a transverse hanger bar, slidably mounted on the said tracks and capable of horizontal movement along the said tracks beyond the confines 20 of the cabinet when the cabinet door is open.
4. A clothes vault, comprising in combination, an insulated cabinet having spaced top, bottom, front, rear and side walls, the said front wall having an insulated door hingedly mounted thereon, 25 an air conditioning means including a humidifying unit and a humidostatically and thermostatically controlled refrigerating unit mounted within the said cabinet, the said refrigerating unit having a vertically extending expansion coil suspended from the top of the cabinet intermediate the said side walls, the said humidifying unit having an evaporating trough disposed below and in close spaced relationship with the expansion coil, capable of collecting the drip from the expansion 30 coil, the said evaporating trough having a covering of porous material of relatively large surface area, and garment supports mounted in the cabinet proximate to the expansion coil.
